UNITED STATES PATENT OFFICE

ARTHUR L. BLAKESLEE, OF KALAMAZOO, MICHIGAN, ASSIGNOR TO KALAMAZOO STOVE COMPANY, OF KALAMAZOO, MICHIGAN

DESIGN FOR A COOKING STOVE OR SIMILAR ARTICLE

Application filed May 14, 1932. Serial No. 43,808. Term of patent 7 years.

To all whom it may concern:

Be it known that I, ARTHUR L. BLAKESLEE, a citizen of the United States, residing at the city and county of Kalamazoo, State of Michigan, have invented a new, original, and ornamental Design for a Cooking Stove or Similar Article, of which the following is a specification, reference being had to the accompanying drawing forming a part thereof, in which the figure represents a perspective view of a cooking stove showing my new design.

I claim:

The ornamental design for a cooking stove or similar article, as shown.

ARTHUR L. BLAKESLEE.
